UNITED STATES PATENT OFFICE.

CHARLES I. WILLIAMS, OF UTICA, NEW YORK.

WATER-GAGE AND CHECK-VALVE.

1,096,481.

Specification of Letters Patent. Patented May 12, 1914.

Application filed May 23, 1907. Serial No. 375,223.

To all whom it may concern:

Be it known that I, CHARLES I. WILLIAMS, a citizen of the United States, residing at Utica, in the county of Oneida and State of New York, have invented certain new and useful Improvements in Water-Gages and Check-Valves, of which the following is a specification, reference being had therein to the accompanying drawing.

10 My invention relates to an improved water gage and check valve, and I declare that the following is a full, clear, concise and exact description thereof, sufficient to enable one skilled in the art to make and use the same, 15 reference being had to the accompanying drawings in which like letters and numerals refer to like parts throughout.

In a device of the character described there are certain features or elements which 20 are essential and which are related to the uses to which the article is to be put.

The ordinary construction and uses of the present mechanism are well understood. But 25 various conditions and emergencies are to be considered. For instance, the glass of such a device sometimes breaks while under boiler pressure and the pieces are apt to do serious harm as also the steam and water which consequently escape. To meet such 30 cases various means have been proposed to prevent the glass pieces from flying and automatically shut off the steam and water. Corrosion of the interior parts is, also, an objection to the use of some styles of such 35 articles, as also the inconvenience of access in case of repairs or cleaning and of assembling the parts of the gage and check. Furthermore, economy of manufacture is a desideratum, together with the capability 40 of the device to answer all the demands of its use.

The construction which I here describe and illustrate in one form comprises several new features, being designed to meet the 45 several requirements and being also of a convenient and economical form and style.

In the drawings Figure 1 is a side view of a gage, the casing being shown in section. Fig. 2 is a bottom view. Fig. 3 is a 50 partial view as in Fig. 1, showing the valve in a different position, the dotted lines in Figs. 1 and 3 showing different positions of operative parts. Figs. 4, 5, and 6 show modifications. Fig. 7 is a partial sectional view 55 on line 7-7 of Fig. 1.

Referring to the figures in detail, 1 is the casing which is adapted at one end, 2, to be mounted on the water column or boiler and at the other end, 3, is adapted to receive the usual valve stem 4 and mountings. It is to 60 be noted that the casing is of a single casting of compact form and symmetrical outline. The interior of the casing is divided by a partition wall into two chambers, one of which, 5, receives a check or valve disk 65 13, one wall being bored for plug 6, by the removal of which convenient access is given to the interior for the assembling of the parts and for cleaning the interior in case the style of casing as shown in Fig. 1 is 70 used. Otherwise the casing may have the form shown in Fig. 5, for the purpose to be mentioned. The other chamber, 7, contains valve members, and its wall is bored for the mounting of a pet-cock, the bore being 75 closed by plug 8 when the casing with its parts is used at the upper end of the water gage, the construction of the same being such that it can be used at either top or bottom by simply inverting it and replacing the 80 plug 8 with a pet-cock, not shown, or vice versa. The wall of chamber 7 is also bored to receive the usual bushing and washer to support the water-glass tube 9 of the gage.

The member 10 which has the valve seats 85 consists of a thimble shown as screw-threaded exteriorly to fit into a bore in the partition in the interior of the casing between the chambers 5 and 7, whereby I provide renewable seats. The thimble is made of 90 non-corrosive material, since corrosion of the parts in such a device destroys its use. At the end toward chamber 7 the thimble terminates in a bevel as shown, the valve 11 being formed of a disk with a corresponding 95 bevel to contact with the seat when the valve stem is turned. The beveled end of the valve seat is notched at opposite points, 12, 12, so that it can be easily screwed into place, being inserted through the opening 100 provided for the valve-stem bushing. At the opposite end, the thimble when seated, projects slightly beyond the wall of the casing. Thus the thimble has a valve-seat at each end. By having this thimble easily removable I provide renewable valve-seats which is an important feature. Suitable closure means may be provided to close the valve at the other valve-seat, as member or disk 13.

The valve-stem 4 is extended in member 110

14 beyond the valve disk 11 and at a distance from the disk has a shoulder 15 and extends beyond that point in a smaller stem 16 on which the check valve or disk 13 is 5 slidably mounted, the stem being capped by screw 17. The threaded portion by which valve-stem 4 is mounted in the casing is of limited length, so that it can be unscrewed or withdrawn a less distance than that between 10 shoulder 15 and screw or cap 17. The form and proportion of the parts is such, also, that withdrawal of the stem cannot force the disk 13 to the seat nor hold it there by use of the valve.

15 In case a gage-glass breaks and a new one is put in, sudden admission of steam is likely to break the glass and for that reason a small leakage is usually provided at or near the check or safety valve. In some cases 20 this is done by guttering the valve-disk, but that is not satisfactory since corrosion is apt to close the gutter. In my design I provide a minute sluice 18 through the non-corrosive thimble 10 which permits 25 slight leakage, not enough to interfere with the insertion of a new glass but sufficient to allow the glass to be gradually filled and the equilibrium of pressure to become reestablished. The other means to which I referred 30 as a provision for safety of the devices consists in surrounding the gage-glass by a plurality of rods 19, mounted in disks 20 adjacent each end of the glass. The use of two 35 or more such rods in merely assembling the parts of such a device is familiar but not with reference to the safety of the construction. An inclosing tube has also been used, slotted for observation of the glass, but that is inconvenient. I provide a plurality of 40 such rods, which incidentally perform the holding function, but act as guards and prevent the promiscuous flying of broken glass while it allows sight of the glass from any point. The rods may be of such size and as 45 closely arranged as desired.

I have spoken of by-pass 18, but in Fig. 4 I illustrate another means of providing this 50 which consists in having the stem 16 slightly channeled longitudinally, as at 21, to allow proper amount of leakage, or if desired the support of disk 13 on the stem may be made 55 loose enough, as in Fig. 7, to permit proper leakage. In Fig. 6 is shown a different by-pass in thimble 10.

55 I have pointed out the fact that the casing is made of simple and cheap form and each casing is interchangeable, for use at the top or bottom. In Fig. 1 I show one wall bored 60 for plug 6 whereby convenient access is had to chamber 5. A form of casing is indicated in Fig. 5 in which no provision is made for such plug, it being possible to assemble the parts without providing for such access.

65 It will be noticed that the outside diam-

eter of the thimble 10 is greater than that of the disk 13.

In assembling the parts the disk is dropped into chamber 5, the thimble 10 is screwed into place, the valve and stem inserted, the valve stem picking up the disk which, by proper handling of the casing, slips down the stem, and screw 17 is inserted by proper means operating through outlet member 2, or, if preferred the outlet member 70 may have sufficient diameter to allow insertion of disk 13 therethrough, as in Figs. 1 and 2. When valve 13 has been forced to its seat, equilibrium of pressure is established through the by-pass, or equivalent 75 means. Turning the stem 4 to the right, or inscrewing of the stem, forces valve or disk 13 into its chamber and opens the valve. While the withdrawal of the stem, if effected without changing the contacting surfaces 80 of the stem and the disk, or if the contact of the two was at all close, might draw disk 13 back, it is found in actual use that, by reason of the looseness of such contact and the fact that the contact surfaces are continually changed through the rotation of the 85 stem, the latter can be withdrawn without drawing the disk 13 back to its seat.

90 While I have shown the invention in one form with certain modifications, it is evident that other changes may be made without departing from the spirit and scope of the invention.

Having described my invention, what I claim as new and desire to secure by Let- 100 ters Patent, is:

1. In a device of the character described, a casing, adapted for use at either end of a water gage, the casing having a partition therein, a removable thimble inserted in the 105 partition, the said thimble consisting of a non-corrosive material removably mounted and having a valve-seat at each end, a valve-stem with a valve-disk thereon to close one end of the thimble and a valve-disk slidably 110 mounted thereon to close the other end of the thimble, substantially as described.

2. In a device of the character described, a casing, a removable non-corrosive thimble 115 therein having a valve-seat at each end thereof, a valve-stem with a disk fixed thereon to close one valve-seat and a disk movable on the stem to close the other valve-seat, the valve-stem being formed to be stopped in opening the former valve before the latter disk is forced to its valve-seat, substantially as described.

3. In a device of the character described, a casing having a partition therein, a thimble in the partition having a valve-seat on each side thereof and a by-pass therethrough, a valve-stem passing through the valve-seats, disks on the stem adapted to close each valve-seat, the interior length of the stem 125 when in its extreme outward position being 130

greater than the distance between the disks in their extreme separated position, substantially as shown.

4. A device of the character described comprising an integral casing having a wall therein providing two interior chambers, a non-corrosive thimble screw-mounted in the wall and directly connecting the chambers and having a by-pass therein, a valve-stem 5 extending through one chamber and through the thimble and into the other chamber in reduced form, means freely slidable on the valve-stem and adapted to close one of the valve-seats of the thimble, substantially as 10 described.

5. In a device of the character described,

a casing, a valve-seat, a valve stem with its inner end free, an automatic check-valve-disk mounted to slide on the free end of the stem, the stem being provided with means 20 to force said disk from the seat to open the valve, the inclosed portion of the stem when in extreme outer position of the valve-stem extending beyond the said disk when in position against the valve seat, substantially 25 as described.

In testimony whereof I affix my signature in presence of two witnesses.

CHARLES I. WILLIAMS.
